UNITED STATES PATENT OFFICE

2,544,688

COMBINED CLIPBOARD AND FLASHLIGHT
STRUCTURE

Kenneth E. Kelley, Niagara Falls, N. Y.

Application November 23, 1946, Serial No. 711,881

8 Claims. (Cl. 240—6.4)

1

This invention relates to portable writing equipment and particularly to registers or devices adapted for releasably holding one or more sheets of paper in such manner as to permit writing or drawing thereon while the register is being held by the writer or another person.

It is an object of the invention to provide an improvement in devices of the type above mentioned whereby their usefulness will be increased. Specifically, it is an object of the invention to provide a device of this character which is provided with means for illuminating the writing surface. A further object of the invention is to provide such an illuminating means which can be readily removed and thus be used to furnish general illumination when required.

Other objects of the invention are to provide a register of the type above mentioned which is simple, rugged, and convenient to use and which is inexpensive to manufacture.

The foregoing, and other objects which will be apparent as the invention is described, may be accomplished by a construction such as is disclosed in the following description and the accompanying drawings.

In the drawings:

Figure 1 is a perspective view of a register in accordance with the present invention;

Figure 2 is another view of the improved register according to the invention with the cover raised in the position it occupies during the use of the register for writing;

Figure 3 is a top view of the register with the lamp removed showing more clearly the lamp mounting means; and

Figure 4 is a view of a lamp of a style which is particularly well adapted for use with the improved register of the present invention.

As shown in the drawings and particularly in Figure 1, the register or clipboard generally is designated by the numeral 1. It comprises as major parts a back or bottom plate 2, a top plate or cover 3a and a clamping plate 3b. Plates 2 and 3b are attached or joined together by movable, flexible means, shown in the illustrated embodiment as hinge 5. Cover 3a is preferably connected to clamping plate 3b by a hinge, shown at 4. Clamping plate 3b is resiliently urged toward contact with bottom plate or back 2 by springs 6 mounted on hinge 5 and bearing against plate 2 and clamping plate 3b.

By the construction above described there is provided a resilient clamping means between plate 3b and back 2 which is adapted to securely hold one or more sheets of paper such as a pad designated by the numeral 7. Back 2 and cover 3a are preferably formed of sheet metal such as aluminum but if desired either or both may be of other suitable material such as wood, fiberboard or plastic.

2

Adjacent to the hinged end of cover 3a there is provided an orifice 8 which is covered by a lamp housing 9. Housing 9 comprises a body portion 9a and a projecting boss-like portion 10 adapted to receive and hold securely one end of a portable lamp 13. Housing 9 is integral with cover 3a, being either formed in one piece therewith as by molding or integrally attached thereto by any convenient and suitable means such as riveting, welding, soldering or the like. Also attached in suitable manner to cover 3a as by rivet 12a is spring clip 12 adapted to receive and hold the other end of lamp 13.

Lamp 13 comprises a hollow body 15 adapted to contain one or more batteries (not shown), a replaceable bulb 14 mounted at one end of body 15, and a switch 16 mounted at the other end thereof. The end of body 15 carrying bulb 14 is adapted to be inserted in boss-like portion 10 of housing 9 so that bulb 14 projects into body portion 9a. The inside of housing 9 is preferably provided with a reflecting surface 18 adapted to reflect light from bulb 14 in the direction desired. It is also preferred to provide in body portion 9a of lamp housing 9 an orifice 9b which by allowing escape of a small beam of light, serves as a tell-tale or indicator warning that the lamp is on while the register is closed.

From the foregoing details of the invention it is believed that its advantages will be readily appreciated but the following short description of its manner of use will perhaps make them even clearer.

Registers of the general type to which the present invention relates are frequently used by messengers, truck drivers, deliverymen, meter readers and others who must often write on the papers or pad held therein or must have someone else write thereon. In the course of such use there are many occasions when the illumination is insufficient and recourse must be had to striking matches or using a flashlight or the headlights of a car. Obviously such expedients are inconvenient, particularly when the register must be held while writing. With the improved register of the invention this difficulty is completely overcome.

As will be seen from the drawings, when cover 3a is raised to permit writing upon or reading from the pad or paper 7 held against back 2 by clamping plate 3b light from bulb 14, reflected from reflecting surface 18, will shine directly on the surface of the paper or pad. Switch 16 on lamp 13 may be easily operated to turn the light on or off as needed. As shown in the drawings, lamp 13 may be easily removed for replacement of batteries or bulbs and when so removed it may be used in the same manner as any other flashlight.

It will be realized that many of the details of the construction illustrated may be changed without departing from the spirit of the present invention. Thus, for example and not by way of limitation, the shape of the register and the precise means employed for clamping the paper or pad therein may be varied as may also the shapes of housings 9 and lamp 13 and the means for mounting the latter. Therefore it is not intended that the invention shall be considered limited except by the scope of the appended claims.

I claim:

1. In a device of the character described: a back; a cover; a clamping portion attached to said cover and back and bearing against said back, whereby one or more sheets adapted to receive writing or printing may be removably held on said back; said cover having an opening therethrough, and a lamp housing surrounding said opening and extending outwardly from said cover on the side away from said back and having a lamp receiving portion; said housing further having a light-reflecting interior surface adapted to reflect light from its interior through said opening to illuminate the inside surface of said back when said cover is in raised position.

2. In a device of the character described: a back; a cover having an opening therethrough; a clamping portion movably attached to said back and to said cover and bearing against said back, whereby one or more sheets adapted to receive writing or printing may be removably held on said back; and a lamp housing integral with said cover surrounding said opening and extending outwardly therefrom on the side away from said back and having a lamp receiving portion; said housing further having a light-reflecting interior surface adapted to reflect light from its interior through said opening to illuminate the inside surface of said back when said cover is in raised position.

3. In a device of the character described: a back; a cover having an opening therethrough; a clamping portion hinged to said back and to said cover and bearing against said back, whereby one or more sheets adapted to receive writing or printing may be removably held against the inside of said back; and a lamp housing integral with said cover surrounding said opening and extending outwardly therefrom on the side away from said back, said housing having a portion adapted to receive the light-emitting end of a removable, portable lamp, and said housing further having an interior surface adapted to reflect light from its interior through said opening to illuminate the inside surface of said back when said cover is in raised position.

4. In a device of the character described: a back; a cover having an opening therethrough; a clamping portion hinged to said back and to said cover; spring means operatively connected to said clamping portion and said back and causing said clamping portion to bear against said back, whereby one or more sheets adapted to receive writing or printing may be removably held against the inside of said back; and a lamp housing surrounding said opening extending outwardly from said cover on the side away from said back and having a portion adapted to receive the light-emitting end of a removable, portable lamp, said housing further having an interior surface adapted to reflect light from its interior through said opening to illuminate the

inside surface of said back when said cover is in raised position.

5. In a device of the character described: a back; a cover having an opening therethrough; a clamping portion attached to said cover and back and bearing against said back, whereby one or more sheets adapted to receive writing or printing may be removably held on said back; a lamp housing surrounding said opening extending outwardly from said cover on the side away from said back and having a lamp receiving portion; a removable, portable lamp having a light-emitting end and switch means; said light-emitting end extending into and being held by said lamp receiving portion; and additional means attached to said cover for holding said lamp in position; said housing further having means therein adapted to cause light from said lamp to illuminate the inside surface of said back through said opening when said cover is in raised position.

6. In a device of the character described: a back; a cover having an opening therethrough; a clamping portion movably attached to said back and to said cover and bearing against said back, whereby one or more sheets adapted to receive writing or printing may be removably held on said back; a removable, portable lamp mounted on said cover and having switch means and a light-emitting end; and a lamp housing surrounding said opening integral with said cover and extending outwardly therefrom on the side away from said back; said housing having a lamp receiving portion into which the light-emitting end of said lamp extends and an interior light-reflecting surface whereby light from said lamp illuminates the inside surface of said back when said cover is in raised position.

7. In a device of the character described: a back having paper clamping means thereon; a cover having an opening therethrough movably attached to said back; a removable, portable electric lamp mounted on said cover and having switch means and a light-emitting end, said light-emitting end being positioned adjacent to but outside said opening, and shielding means surrounding said light-emitting end on the side away from said back adapted to direct light therefrom through said opening.

8. In a device of the character described: a back having paper clamping means associated therewith; a cover movably attached to said back and having an opening therethrough; a portable electric lamp removably mounted on the outside of said cover; and means on the outside of said cover adapted to direct light from said lamp through said opening.

KENNETH E. KELLEY.
